ADJUSTABLE WAISTBAND

Samuel Kreps, New York, N. Y.

Application January 25, 1946, Serial No. 643,356

2 Claims. (CL 2-237)

1

This invention relates to an adjustable waist construction for garments, particularly men's and ladies' trousers and slacks.

It is the object of the present invention to provide an adjustable waist construction for garments which is economical to manufacture and is of pleasing appearance and comfortable to the wearer.

It is a further object of the present invention to provide an adjustable waist construction for trousers or slacks which may be adjusted within the limits of several sizes according to the needs of different wearers, or the needs of the same wearer from time to time as the wearer may experience differences in the size of the waist, which adjustment requires no ripping or sewing operations, and which at the same time renders the adjustable waist indiscernable and no different from waist constructions of conventional trousers.

It is a further object of the invention to incorporate an abdominal support as part of the waist construction, which may be done at an insignificant cost in the manufacture of the improvement in trouser waists in accordance with the present invention.

It is a further object of the invention to incorporate novel belt effects as part of trouser constructions which would enhance the novelty and consequently the saleability of slacks, knickers and similar apparel in view of the special appeal of such arrangements to wearers of sporting apparel and the like.

While efforts have been made heretofore to obtain adjustable waist constructions for trousers and other wearing apparel, these have failed to meet with public favor for different reasons, such as the additional cost of incorporating such adjustable expedients in the apparel construction, the limited range of adjustability afforded by such arrangements and the bunching and puckering resulting therefrom, tending to render the fitting of the garment unsatisfactory and unsightly as a result thereof.

All of such objectionable features are eliminated by the present invention which proceeds upon the principle of adjusting the rear of the garment in place and thereafter adjusting the degree of overlap of the front of the garment over the edges of the rear to obtain the desired waist size quickly and easily by manipulation at the front of the garment and as a natural incident to the buckling-up of the garment for use every time the same is worn. It is significant that both adjustments are made at the front of

2

the garment where such may be done conveniently while putting on the same by the wearer.

Other objects and purposes will appear from the detailed description of the invention following hereinafter, taken in conjunction with the accompanying drawing, wherein

Fig. 1 is a perspective view of the adjustable waist construction applied to a pair of trousers from the front thereof; and

Fig. 2 is a perspective view of the adjustable waist construction from the rear thereof.

In the drawings the upper portion of a pair of trousers T is shown embodying a rear portion which is manufactured in the conventional manner with a central seal 4' therein, and which is adapted to be sewn to the fronts of the leg portions 2 and 3 at the side seams 15. The constituent elements of the trousers or slacks are manufactured in the usual way, requiring no special operations, and pockets may be provided in both the front and back portions as desired. Side or top pockets P are provided in the front portions 2 and 3 at any desired inclination, as indicated in Fig. 1, and the rear pockets P' may be incorporated in the rear portion 4 in the conventional manner.

The only modification in the trouser construction over conventional trousers involves the provisions of flaps or extensions 16 and 17 at the upper part of the rear portion 4 beyond the terminals 20 of the side seams 15. Cooperating strap members 11 are attached by sewing or otherwise to the free ends of the flaps 16 and 17 and serve to fasten the rear portion of the garment around the waist of the wearer. The width of these strap elements 11 may be varied so that with wider widths they may serve the function of abdominal supporters. Thereby the need of extraneous devices such as girdles, bands or the like is eliminated in cases where some form of abdominal support is desirable.

The adjustment for the waist in accordance with the present invention is obtained by varying the degree of overlap of the frontal portions 6, 7 of the trouser fronts 2 and 3, respectively, over the rear flaps or extensions 16 and 17. This overlap is made smoothly, with no bunching or puckering as a result of the large extent of freedom of the frontal portions 6 and 7 from attachment with the rear portion in view of the termination of the side seams at points 20, at approximately the level of the lower ends of the side pockets P. Therefore the front portions 6 and 7 may accommodate themselves into close contact with the rear portions 16 and 17 to render imperceptible

the slits 4 and 5 whereat the rear portion 1 is not sewed to the frontal parts 6 and 7.

In accordance with the invention, a neat and convenient mode of positioning the frontal portions over the rear portion at the front of the trousers is attained by the provision of belt members attached to the extremities of the frontal portions 6 and 7 which are made to pass around the rear portion 1 and are thereafter brought to the front of the garment to effect a convenient and rapid fastening of the waist whereat the same is readily observed by the wearer. This arrangement is clearly illustrated in Fig. 2 which shows the belt portion 8 fixed to the extremity of the frontal portion 6 which passes around the rear to the front of the garment at 8' and terminates in the buckle 18. Likewise the belt portion 9 is attached to the extremity of the frontal portion 7 and passes around the rear portion of the garment through an opening 19 provided in the belt portion 8 at approximately the mid-point thereof, wherefrom it passes to the front of the garment 9' so that the extremity thereof may cooperate with the buckle 18. Any suitable clasp may be employed at the extremities of the straps 8' and 9' to obtain an interengagement between the parts in lieu of the buckle and openings shown in the drawings.

Novel dress effects may be obtained by the use of leather belts, or belts of different fabric and plastic materials which are attached to the extremities of the frontal portions 6 and 7. Of course, if desired, the same material of which the trousers are made may be used for the belt members 8 and 9. As is well understood in the art, belt loops 14 are provided on the rear portion of the garment, and belt loops 14' on the front thereof in any desired number to provide an effective guide for the belt structure.

By varying the extent of the rear flaps or projections 16 and 17, and by adjusting the upper limit 20 of the side seam stitching 15, the trousers are capable of an adjustment within a range of at least four inch variations in waist measurements, so that a merchant need stock a correspondingly smaller number of units in order to meet the needs of his trade.

The additional cost of manufacture entailed by the provision of the belt elements applied to the frontal portions is offset by the furnishing of a belt with the garment as well as by the simplified finishing operation of the waist portions. The manufacturing steps are such as do not increase materially the cost of manufacture thereof and are more than offset by the economies resulting in the course of distribution and use of the trousers, by the elimination of the need for any initial alterations for waist variations and the satisfaction to the wearer of having a trouser construction which can be adjusted to the variations in waist measurement in the course of time.

Although the invention is of particular utility in the provision of adjustable waistbands for trousers, the features thereof may be applied as well to other articles of apparel such as skirts, dresses and the like. While I have described my

invention as embodied in a specific form and as operating in a specific manner for purpose of illustration, it should be understood that I do not limit my invention thereto, since various modifications will suggest themselves to those skilled in the art without departing from the spirit of my invention, the scope of which is set forth in the annexed claims.

I claim:

1. A garment embodying an adjustable waist comprising a rear portion and a front portion sewed together at the sides with seams terminating a substantial distance below the waistline, a forwardly disposed extension on each side of the rear portion above each seam, a frontal part on each side of the front portion overlapping the respective adjoining extension of the rear portion to obtain an adjustment of the waist dimension in dependence upon the extent of overlap of said frontal parts over said extensions, and a belt member connected to each frontal part passing rearwardly over and around the rear portion and to the front of the garment for providing a convenient adjustment at the front of the garment for the extent of overlap of said movable frontal parts over said rear portion and extensions thereof.

2. A pair of trousers embodying an adjustable waist comprising a rear portion with forwardly disposed side extensions at the upper end thereof, straps connected to said extensions adapted to be clasped together around the abdomen at the front of the wearer, right and left front portions sewed to the opposite sides of said rear portion at side seams terminating at the lower end of said side extensions and a substantial distance below the waistline, the lateral ends of the front portions overlapping said side extensions in variable amounts to obtain an adjustment of the waist dimension depending upon the extent of overlap of said front portions over said extensions, and a belt member connected to each front portion passing rearwardly over and around the rear portion and to the front of the garment for providing a convenient adjustment at the front of the garment for the extent of overlap of said adjustable front portions over said relatively fixed rear portion and side extensions.

SAMUEL KREPS.
